UNITED STATES PATENT OFFICE.

WILLIAM CHARLES ZIEGENFUS, OF KINGSTON, PENNSYLVANIA.

DRUMHEAD.

1,334,343.

Specification of Letters Patent. Patented Mar. 23, 1920.

Application filed July 5, 1917. Serial No. 178,687.

To all whom it may concern:

Be it known that I, WILLIAM C. ZIEGENFUS, a citizen of the United States, residing at Kingston, in the county of Luzerne and 5 State of Pennsylvania, have invented a new and useful Drumhead, of which the following is a specification.

The device forming the subject matter of 10 this application is adapted to constitute a part of a drum, can, pail or other container, and one object of the invention is to provide a simple and inexpensive but absolutely reliable means whereby a cover can be locked in position on a container.

15 Another object of the invention is to provide means whereby access may be had to the edge of the cover, to permit the cover to be pried out.

It is within the province of the disclosure 20 to improve generally and to enhance the utility of devices of that type to which the present invention appertains.

With the above and other objects in view 25 which will appear as the description proceeds, the invention resides in the combination and arrangement of parts and in the details of construction hereinafter described and claimed, it being understood that changes in the precise embodiment of the 30 invention herein disclosed can be made within the scope of what is claimed, without departing from the spirit of the invention.

In the accompanying drawings:—

35 Figure 1 shows the invention in top plan; Fig. 2 is a section taken approximately on the line 2—2 of Fig. 1;

Fig. 3 is a section taken approximately on the line 3—3 of Fig. 1;

40 Fig. 4 is a perspective view showing a drum or container whereunto the device forming the subject matter of this application has been applied.

In the accompanying drawings, the number 45 1 indicates a can, ordinarily made of metal. Assembled as indicated at 2, in any suitable manner, with the end of the can 1 is a top 3 which preferably is made of metal, the top 3 being depressed or spaced from 50 the end of the can 1, as will be clearly understood from Fig. 2. The top 3 is prolonged in a direction approximately parallel to the axis of the can 1 to form an annular shoulder 4, which is extended in a direction approximately at right angles to the 55 axis of the can 1 to form an annular flange

5, the inner edge of the flange 5 being extended in a direction approximately parallel to the axis of the can 1 to form an annular lip 6.

The numeral 7 denotes a cover, ordinarily made of metal and including an angularly disposed rim 8 which fits closely within the lip 6. The outer edge of the rim 8 is fashioned into a bead 9 which rests on the flange 65 5. It is to be observed that the rim 8, engaging the lip 6, spaces the bead 9 from the shoulder 4, as indicated at 10, so that a screw driver or other suitable tool may be inserted between the bead 9 and the 70 shoulder 4, to permit the cover 7 to be pried loose.

Any desired number of pivot elements 11 are mounted, in circumferentially spaced relation, in the top 3. Buttons 12 are 75 mounted intermediate their ends on the pivot elements 11, to swing thereon. The buttons 12 overhang the bead 9 and hold the cover 7 in place, the buttons being held down closely on the top 3, so that they can 80 be turned only when a considerable force is applied to the button. The buttons 12 are provided along their longitudinal edges with projecting flanges 14. The flanges serve to reinforce the buttons and to prevent them from bending. Further, a tool 85 of any kind may be inserted between the flanges 14, to facilitate the rotation of the buttons 12 on the pivot elements 11. When the buttons 12 are rotated on the pivot elements 11, as aforesaid, to clear the bead 9 of the cover 7, the cover may be pried loose, as described, by means of a screw driver or other tool inserted into the space 10. The bead 9 is disposed flush with the outer 90 surface of the top 3, so that the buttons 12 may engage over the beads, as shown in Fig. 2. The outer ends of the buttons 12 bear with a strong frictional hold on the upstanding rim 20 of the top, as indicated at 21, and 95 consequently an accidental turning of the buttons is not likely to take place.

Having thus described the invention, what is claimed is:—

In a device of the class described, a receptacle; a top having an inverted U-shaped bead receiving the end of the receptacle, the top being prolonged parallel to the axis of the receptacle to form a shoulder, the shoulder being extended at right angles to the 110 axis of the receptacle to define a flange having an annular inwardly extended lip

disposed parallel to the axis of the receptacle; a cover provided with a rim fitting closely in the lip, the rim having a bead engaged with the flange and spaced from the shoulder, the outer surface of the bead being flush with the outer surface of the top; and a button pivoted intermediate its ends on the top, one end of the button overhanging the bead, the other end of the button being frictionally engaged with the U-shaped bead, the U-shaped bead bearing

throughout its entire width against the receptacle to withstand the thrust of the button, the button having reinforcing side flanges facilitating the turning of the button and increasing the hold of said other end of the button on the U-shaped bead. 15

In testimony that I claim the foregoing as my own I have hereto affixed my signature.

WILLIAM CHARLES ZIEGENFUS.
